UNITED STATES PATENT OFFICE.

EDWIN BERTRAM DALLIN, OF ARLINGTON, MASSACHUSETTS.

ELECTROMAGNETIC-WAVE-RECEIVING SYSTEM.

1,202,168.

Specification of Letters Patent. Patented Oct. 24, 1916.

Application filed August 14, 1915. Serial No. 45,549.

To all whom it may concern:

Be it known that I, EDWIN B. DALLIN, a citizen of the United States, and a resident of Arlington, in the county of Middlesex and State of Massachusetts, have invented 5 a new and useful Improvement in Electromagnetic-Wave-Receiving Systems, of which the following is a specification.

My invention relates to electromagnetic-wave receiving-systems and its object is to simplify the construction and improve the efficiency of the same in the manner herein-after set forth.

An illustrative embodiment of my invention is shown diagrammatically in the drawing which accompanies and forms a part of this specification; but it is to be understood that various modifications may be made both in the particular apparatus and in the circuit arrangements therein disclosed without departing from the principle of my invention.

In the drawing, V represents a receiving conductor of any suitable construction, 25 herein shown as an elevated conductor, connected to earth E through the inductance L_1 , and condenser C_1 , both of which preferably are adjustable. The circuit which includes the inductance L_2 and condenser C_2 , both of 30 which as shown preferably are adjustable, is a tuned receiving circuit, operatively connected with which in any suitable manner is a detector D and signal-indicating device T. In the present instance, D represents a crystal detector and T a telephone, and a condenser C may be shunted across the terminals of said telephone. The inductances L_1 and L_2 are arranged at right angles to each other so that their mutual inductance is substantially zero and there is no electrical reaction between the receiving conductor and the tuned receiving circuit.

For the purpose of conveying the energy from the receiving conductor to the tuned 45 receiving circuit, I employ an open circuit which includes the coil $L L'$, each consisting of one or more turns, three turns being shown in the diagram, and said coils are preferably closely coupled with the ends of 50 the inductances L_1 , L_2 which are remote from the adjustable contacts co-operating with the same. The said open circuit should have very low resistance and practically no capacity, and preferably it is constructed 55 of stranded wire.

Inasmuch as the reduction of mutual inductance between the inductances L_1 , L_2 is effected by the position of the same at right angles as distinguished from spatial separation, it is possible to locate the several coils 60 and condensers, as well as the associated apparatus, in a relatively small and portable casing, and such casing may be provided with the usual instrumentalities for varying the inductance and capacity of the several 65 coils and condensers in the usual manner which is well understood and requires no description herein. It will be noted that the translation of energy from the receiving conductor to the tuned receiving circuit is 70 effected electrostatically.

I have found that for the same degree of selectivity or sharpness of tuning, the signals received by my system are of greater intensity, other things being equal, than 75 those received by an equivalent loosely-inductively coupled system, and conversely with a given signal intensity, the selectivity 80 of my system is superior to that of such equivalent loose-coupled system. I have also 85 found that with a given signal intensity the selectivity of my system is much higher than that obtained, other things being equal, when a closed circuit having very low resistance and substantially no capacity, is inductively related with the inductances L_1 , L_2 , both when the latter are arranged as above set forth or are so remote from each other that their mutual inductance is substantially zero.

Having thus described one illustrative embodiment of my invention, without however limiting the same thereto, what I claim as new and desire to secure by Letters Patent 95 is—

1. In an electromagnetic-wave receiving system, a receiving conductor including an inductance, a tuned receiving circuit including an inductance, said inductances being arranged at right angles to each other, so that their mutual inductance is substantially zero, and an open circuit inductively associated with said inductances.

2. In an electromagnetic-wave receiving system, a receiving conductor including an inductance, a tuned receiving circuit including an inductance, said inductances being arranged at right angles to each other, so that their mutual inductance is substantially zero, and means for electrostatically trans-

lating energy from said receiving conductor to said receiving circuit.

3. In an electromagnetic-wave receiving system, a receiving conductor, a tuned receiving circuit, and an open circuit inductively connected with said receiving conductor and said receiving circuit.

In testimony whereof, I have hereunto subscribed my name this 13th day of August, 1915.

EDWIN BERTRAM DALLIN.
